REMOTE CONTROL APPARATUS

Harry C. Vantassel, Pittsburgh, Pa., assignor to
The Union Switch & Signal Company, Swiss-
vale, Pa., a corporation of Pennsylvania

Application January 21, 1929, Serial No. 334,081
Renewed July 3, 1931

61 Claims. (Cl. 246—3)

My invention relates to remote control apparatus, and particularly to apparatus for safely controlling traffic governing devices such as railway switches and signals from a distant point.

5 One feature of my invention is the provision of means for separately controlling a switch and associated signals over three conductors by a switch lever and a signal lever respectively, and for separately controlling these two levers over 10 the same three conductors by the switch and the signals respectively.

I will describe one form of apparatus embodying my invention, and will then point out the novel features thereof in claims.

15 The accompanying drawing is a diagrammatic view showing one form of remote control apparatus embodying my invention.

Referring to the drawing, the reference characters 1 and 1a designate the track rails of a 20 stretch of a main railway track AA connected, by means of a switch F, with a passing siding BB. The portion of track AA and of siding BB adjacent switch F are divided from adjoining portions of track AA and siding BB, respectively, by 25 insulated joints 2 to form what is known as a detector track section for switch F. This detector track section is provided with a track circuit comprising a track battery 3 and a track relay T, for controlling the switch and signals in accordance 30 with traffic conditions in the stretch.

Eastbound traffic, that is, traffic moving from left to right, as shown in the drawing, is governed by signals S1 and S2 which are mounted on a common mast 147 and which as here shown are of 35 the semaphore type. Signal S1 governs traffic moving over switch F in its normal position on the main track AA, whereas, signal S2 governs traffic moving over switch F in its reverse position onto siding BB. Westbound traffic moving over track 40 AA is governed by a signal S3, and westbound traffic moving from siding BB to main track AA is governed by a signal S4.

45 Switch F is controlled by a polarized switch control relay G, which is in turn controlled by a manually operable switch lever V1 having normal and reverse positions N and R, respectively and lock positions X, B, D and Y. Lever V1 is equipped with nine contacts 45, 71, 125, 126, 6, 7, 8, 50 68 and 69. Contacts 45 and 71 serve as a pole-changer for operating relay G. Contact 45 is closed when lever V1 is at points A or B or in any intermediate position, and contact 71 is closed while lever V1 is at points D or E or in any intermediate position. Contacts 125 and 7 are closed 55 while lever V1 is in its N position only; contact 6

is closed while lever V1 is at point C only; contacts 126 and 8 are closed while lever V1 is in its R position only; contact 68 is closed while lever V1 is at points B or X or in any intermediate position; and contact 69 is closed while lever V1 is at points D or Y or in any intermediate position. Switch indication means comprising an electric lock L1 arrests the movement of lever V1 at positions X and D while lever V1 is being operated from its N to its R position, and arrests the movement of lever V1 at positions Y and B while lever V1 is being operated from its R to its N position.

As here shown, switch F is operated by a switch machine comprising a motor g having an armature 148 and a field winding 149. The operating 15 circuits for motor g are controlled in the well known and usual manner by polarized relay G, and form no part of my present invention and are therefore omitted from the drawing.

A switch indication relay K is also controlled 20 in the well known and usual manner by a pole-changer operated by switch F, and the control circuits for relay K are therefore also omitted from the drawing. A second switch indication relay KK is associated with and controlled in part 25 by lever V1, and is controlled in part also by the first switch indication relay K and by the switch control relay G. Relay KK is provided with a normal and a reverse winding having a common terminal to which wire 65 is connected. When 30 current flows through the normal winding, the contacts of relay KK are closed in the normal direction, and when current flows through the reverse winding, the contacts of relay KK are closed in the reverse direction. The construction of 35 relay KK is such that, when both its windings are de-energized, its contacts remain closed in the direction controlled by the winding which was last previously energized.

40 Signals S1, S2, S3 and S4 are controlled by polarized signal control relay H, which is in turn controlled by a manually operable signal lever V2 having a normal or "stop" position n, a left-hand clear or "proceed" position m, and a right-hand clear or "proceed" position r, as well as a left 45 lock position b, and a right lock position d. Lever V2 is equipped with contacts 43, 145, 75, 63, 19, 20, 21, 138, 139, 90, 89, 96, 97, 128 and 129. Contacts 43, 63 and 19 are closed while lever V2 is in its n position only; contacts 145, 20, 90 and 96 are 50 closed while lever V2 is in its m position only; contacts 75, 21, 89 and 97, are closed while lever V2 is in its r position only; contacts 138 and 128 are closed while lever V2 is at points a or b or in any intermediate position; and contacts 139 and 55

129 are closed while lever V2 is at points *d* or *e* or in any intermediate position. Lever V2, when operated to its *r* position, controls the normal energization of relay H for controlling signals S1 5 and S2, and, when operated to its *m* position, controls the reverse energization of relay H for controlling signals S3 and S4. Signal indication means comprising an electric lock L2 arrests the movement of lever V2 at point *b* while lever V2 10 is being returned from its *m* to its *n* position, and arrests the movement of lever V2 at point *d* while lever V2 is being returned from its *r* to its *n* position.

Levers V1 and V2 may be grouped with other 15 similar levers at some central control point such as a train despatcher's office, from which point three conductors comprising a combined switch control and signal indication wire 41, a combined signal control and switch indication wire 60, and 20 a common wire 30 extend to the station at which switch F and the signals S are located.

Each of the signals S1, S2, S3 and S4 operates a 25 circuit controller designated by the reference character *y* with a suffix corresponding to that of the reference character for the signal. Each of these circuit controllers operates three contacts, one of which, such as contact 51 of circuit controller *y1*, is closed while the arm of its signal S1 is in the stop position, the second of which, 30 such as contact 111 of circuit controller *y1*, is closed while the arm of its signal S1 is in a position from three to five degrees away from the stop position, and the third of which, such as contact 85 of circuit controller *y1*, is closed while the 35 arm of its signal S1 is at any point from fifteen to ninety degrees away from the stop position.

Signals S1, S2, S3 and S4, by means of their circuit controllers *y*, control a slow release relay Z. A lock releasing relay Q becomes energized when 40 lever V2 is operated to its *m* or *r* positions for clearing a signal, and becomes deenergized when the signal arm has arrived at a point fifteen degrees away from the "stop" position. Relay Q can also be energized by the operation of a time 45 releasing device W. A neutral "signal clear" indication relay P becomes energized when the arm of any one of signals S1, S2, S3 and S4 has reached the 15 degree point while clearing in response to the operation of lever V2 to its *m* 50 or its *r* position. A stick locking relay M is provided with a pick-up circuit controlled by relay P, and with a stick circuit controlled by relay Q. A polarized signal indication relay I is controlled in part by levers V1 and V2, by signals S1, S2, S3, 55 and S4, by signal control relay H, and by relay Z. Relay I is similar to relay KK, having a normal and a reverse winding and being so constructed that its contacts will remain closed in the direction controlled by the winding last previously energized. An indicator *i*, which in the 60 form here shown is an electric lamp, is controlled in multiple with lock releasing relay Q.

A time releasing device U, which may be of the well known mercury type, is operated by lever V2, 65 being so arranged as to open its contact when lever V2 is operated to its *m* or its *r* position, and to again close its contact upon the lapse of a measured interval after lever V2 has been returned from its *m* to its *b* position, or from its *r* 70 to its *d* position. Release U enters into the control of electric lock L2.

Signals S1, S2, S3 and S4 are controlled in the well known and usual manner by polarized relay H and by a circuit controller operated by switch 75 F, and hence the operating circuits for these

signals, since they form no part of my present invention, are omitted from the drawing.

A source of current, here shown as a battery *t*, is located adjacent switch F, and sources of current, shown as batteries *f* and *h*, are located adjacent levers V1 and V2. 5

Having thus described, in general, the arrangement and location of the various parts of the apparatus embodying my invention, I will now proceed to describe the operation of the apparatus. 10

As shown in the drawing, all parts are in their normal condition, that is, switch F is set for traffic moves along the main track AA, each of the signals S1, S2, S3 and S4 indicates stop, the detector track section is unoccupied, and levers V1 15 and V2 are in their normal positions *N* and *n* respectively. With lever V1 in its *N* position, current is supplied to the normal winding of relay KK by a circuit passing from battery *f*, through wires 4 and 5, contact 7 of lever V1, wire 9, the 20 normal winding of relay KK, and wires 65, 11 and 12, to common terminal 13 of batteries *f* and *h*. With lever V2 in its *n* position, current is supplied to the normal winding of relay I by a circuit passing from battery *f*, through wires 14, 25 15, 16, 17 and 18, contact 19 of lever V2, wire 22, the normal winding of relay I, and wires 23 and 24 to terminal 13. The contacts of relays KK and I are accordingly closed in their normal direction. With switch F in its normal position, relay 30 KK is energized in its normal direction, and hence the normal contacts of relay K are closed. With switch F in its normal position, relay G has been last energized in its normal direction, and hence the normal contacts of relay G are closed. 35

I will now assume that the despatcher desires to clear signal S1 for a move over switch F normal. He accordingly operates lever V2 to its *r* position, thereby supplying current of normal polarity to relay H by a circuit passing from battery *f*, 40 through wires 14, 15, 16, 17 and 18, contact 75 of lever V2, wires 61 and 60, contact 76 of relay G, winding of relay H, wire 77, contact 78 of relay G, wires 79, 80, 81, 30 and 29, contact 28 of relay I, wire 27, contact 26 of relay KK, and 45 wires 25 and 12 to battery terminal 13. Relay H, being thus energized in its normal direction, causes signal S1 to clear, switch F being in its normal position. Upon the operation of lever V2 50 to its *r* position, the control circuit for relay Q and the lighting circuit for lamp *i* are closed, passing from battery *f*, through wires 14, 15, 16, 17 and 93, contact 94 of relay P, wire 95, contact 97 of lever V2, wire 98, winding of relay Q in multiple with lamp *i*, and wire 24 to battery terminal 13. 55

When the arm of signal S1 arrives at a point 15 degrees away from its "stop" position, the circuit for relay P becomes closed at contact 85 of circuit controller *y1*, and current then flows from battery *t*, through wire 41, contact 85, wire 86, contact 87 of relay H, wires 40, 41 and 88, contact 89 of lever V2, wire 91, winding of relay P, and wires 92, 30 and 81 back to battery *t*. Relay P, upon becoming energized, closes the circuit of relay M passing from battery *f*, through wires 14, 15, 16, 17 and 93, contact 102 of relay P, wire 103, winding of relay M, and wires 104, 11, and 12 to battery terminal 13. Due to the energization of relay P, relay Q is again de-energized, and, with relay M now energized, a stick circuit for relay M 70 is completed through back contact 105 of relay Q, this circuit passing from battery *f*, through wire 14, contact 105, wire 106, contact 107 of relay M, winding of relay M, and wires 104, 11 and 12 to battery terminal 13. 75

The operating circuit for signal S_1 , as well as those for signals S_2 , S_3 , and S_4 , is controlled through a front contact of track relay T , and hence, when a train passes signal S_1 in its clear position, the operating circuit for signal S_1 is opened by the shunting of relay T , thereby causing the arm of signal S_1 to return to its "stop" position. When the arm of signal S_1 moves from its "proceed" position to a point which is 15 degrees away from its "stop" position, the circuit for relay P is opened at contact 85 of circuit controller y_1 . The first pick-up circuit for relay Q is then again completed at back contact 94 of relay P , causing relay Q to again become energized. With relay P now de-energized and relay Q energized, both the pick-up circuit and the stick circuit of relay M are open, causing relay M to be de-energized.

During the movement of the arm of signal S_1 from a point 5 degrees to a point 3 degrees away from its "stop" position, relay Z becomes energized by a circuit passing from battery t , through wire 47, contact 111 of circuit controller y_1 , wire 112, the winding of relay Z , and wire 80 back to battery t . Relay Z , being slow releasing, retains its front contact in the closed position as the arm of signal S_1 continues to its "stop" position where a second pick-up circuit for relay Z becomes closed, and current then flows to relay Z , from battery t , through wire 47, contacts 48, 49, 50, and 51 of signal-operated circuit controllers y_4 , y_3 , y_2 and y_1 , respectively, wires 113 and 114, contact 115 of relay H , and wire 116 to the winding of relay Z .

When the train moves out of the detector section while lever V_2 is still in its r position, relay T does not again become energized until the despatcher operates lever V_2 away from its r position causing relay H to become de-energized. The reason for this is that the track relay T is a stick relay having a pick-up circuit which includes back contact 142 of relay H . A stick circuit for relay T includes front contact 143 of relay T in multiple with the pick-up circuit path through contact 142.

When lever V_2 is returned to its d position, the reverse winding of relay I becomes energized by current flowing from battery t , through wire 47, contacts 48, 49, 50, and 51 of circuit controllers y , wires 113 and 117, contact 118 of relay Z , wire 119, contact 120 of relay H , wire 121, contact 122 of relay G , wires 123, 41, 42 and 124, contact 125 of lever V_1 , wire 127, contact 129 of lever V_2 , wire 130, contact 131 of relay P , wire 132, the reverse winding of relay I , wires 23, 24, 12, and 25, contact 26 of relay KK , wire 27, contact 28 of relay I , and wires 29, 30 and 81 back to battery t . The contact of release U having been opened by the operation of lever V_2 to its r position, becomes closed again upon the lapse of a measured interval of time after lever V_2 has been returned to its d position. Reverse contact 133 of relay I being closed, due to the energization of the reverse winding of relay I , and the contact of release U being closed, electric lock L_2 is energized by current passing from battery f , through wires 14 and 15, the contact of release U , contact 133 of relay I , wire 134, contact 135 of release W , contact 136 of relay M , wire 137, contact 139 of lever V_2 , wire 140, winding of lock L_2 , and wires 141, 23, and 24 to battery terminal 13. The operation of lever V_2 can now be continued to the n position.

I will now assume that, while a train occupies the detector track section, the despatcher, unaware of such occupancy, attempts to clear sig-

nal S_1 by operating lever V_2 to its r position as already described. Relay H becomes energized but the operating circuit of signal S_1 , being controlled through a front contact of relay T , continues open, and hence signal S_1 does not clear. Relay Q becomes energized and lamp i becomes lighted, as previously described. Relay P , however, does not become energized, since the circuit for this relay continues open at contact 85 of circuit controller y_1 , and hence lamp i continues to lighted. The despatcher therefore knows that signal S_1 has not responded to the operation of lever V_2 . If he now returns lever V_2 to its d position, the circuit of the reverse winding of relay I becomes closed as previously described, since relay Z has been energized by its second pick-up circuit through contact 115 of relay H . After the lapse of a measured interval of time, release U closes its contact and the despatcher can then complete the return of lever V_2 to its n position.

I will now suppose that the despatcher desires to send a train from track AA to siding BB. Assuming that all parts of the apparatus are again in their normal condition, previously described, the despatcher proceeds to reverse lever V_1 .

When lever V_1 arrives at point A, the circuit for relay G becomes closed at contact 45 of lever V_1 , and remains closed as the movement of the lever is continued to point X. Current therefore flows from battery h , through wires 12 and 25, contact 26 of relay KK , wire 27, contact 28 of relay I , wires 29, 30, and 31, contact 32 of relay H , wire 33, winding of relay G , wire 34, contact 35 of relay T , wire 36, contact 37 of relay Z , wire 38, contact 39 of relay H , wires 40, 41, and 42, contact 43 of lever V_2 , wire 44, contact 45 of lever V_1 , and wire 46 back to battery h . Relay G , upon thus becoming energized, closes its neutral contacts. Its polar contacts, however, do not change position since its energization is now in the normal direction which is the direction in which it was last previously energized by the return of lever V_1 to the N position.

Since switch F is in its normal position, relay K is energized in its normal direction and hence its polar contacts are closed in their normal position. The reverse winding of relay KK now becomes energized by current flowing from battery t , through wire 47, contacts 48, 49, 50 and 51 of circuit controllers y , wire 52, contact 53 of relay T , wire 54, contact 55 of relay K , wire 56, contact 57 of relay G , wire 58, contact 59 of relay G , wires 60, 61 and 62, contact 63 of lever V_2 , wire 64, the reverse winding of relay KK , wires 65, 11 and 25, contact 26 of relay KK , wire 27, contact 28 of relay I , and wires 29, 30 and 81 back to battery t .

When lever V_1 arrives at point X, the circuit of lock L_1 is completed at contact 68 of lever V_1 , and current therefore flows from battery f , through wire 4, contact 66, wire 67, contact 68 of lever V_1 , winding of lock L_1 , and wires 10, 11 and 12 to battery terminal 13. The operation of lever V_1 can now be continued past locking point X to locking point D.

As lever V_1 passes point C, the normal winding of relay KK becomes energized by current flowing from battery f , through wires 4 and 5, contact 6 of lever V_1 , wire 8, the normal winding of relay KK , and wires 65, 11 and 12 to battery terminal 13. Normal contact 26 of relay KK therefore becomes again closed.

At point D, the reverse control circuit of relay G is completed through contact 71 of lever V_1 , and current now flows from battery f , through

wires 4, 5 and 70, contact 71, wire 44, contact 43 of lever V2, wires 42, 41 and 40, contact 39 of relay H, wire 38, contact 37 of relay Z, wire 36, contact 35 of relay T, wire 34, winding of 5 relay G, wire 33, contact 32 of relay H, wires 31, 30 and 29, contact 28 of relay I, wire 27, contact 26 of relay KK, and wires 25 and 12 to battery terminal 13. The polar contacts of relay G now become closed in their reverse position, causing switch F to be operated to its reverse position.

Upon the completion of the operation of switch F to its reverse position, relay K becomes energized in its reverse direction and hence closes its 15 contacts in their reverse position. A circuit is now closed for the reverse winding of relay KK. This circuit is the same as previously traced except that it includes, around contacts 55 and 20 57 of relays K and G, respectively, a branch path passing from wire 54, through contact 72 of relay K, wire 73, and contact 74 of relay G to wire 58. The winding of lock L1 is now energized by a circuit which is the same as previously traced except that it passes through contact 25 69 instead of through contact 68 of lever V1. The operation of lever V1 can now be continued to its R position where the normal winding of relay KK again becomes energized by current flowing from battery f, through wires 4 30 and 5, contact 8 of lever V1, wire 9, the normal winding of relay KK, and wires 65, 11 and 12 to battery terminal 13. Contact 26 of relay KK now again becomes closed.

The despatcher now reverses lever V2 to its 35 r position, causing relay H to become energized by the circuit previously traced. With relay H energized in the normal direction, and with switch F in its reverse position, a local operating circuit causes the arm of signal S2 to be operated to its "proceed" position. The 40 operations of relays Q, P and M, and the lighting of lamp i, are similar to those previously described in connection with the clearing of signal S1, and will be readily understood from 45 the drawing without further description.

If, now, the despatcher should desire to return the arm of signal S2 to its "stop" position before a train enters the detector section, he will return lever V2 to its d position as before. 50 Relay P is thus de-energized, but relay M continues energized through its stick circuit. Since relay M is energized, the circuit of lock L2 is open at contact 136 of relay M, and, in order to continue the operation of lever V2 to its n position, the despatcher must operate time release 55 W. A second pick-up circuit for relay Q, and the lighting circuit for lamp i are thereby closed, and hence current flows from battery f, through wires 14, 15, 16 and 99, contact 100 of relay M, contact 101 of release W, the winding of relay 60 Q and lamp i in multiple with each other, and wire 24 to battery terminal 13. Relay Q, upon becoming energized, opens the stick circuit for relay M which is thereby deenergized. The despatcher will now start the operation of release 65 W to its normal position. After a measured interval of time, contact 135 of release W closes, completing the control circuit previously traced for lock L2. The operation of lever V2 can now 70 be continued to its n position.

If, then, the despatcher wishes to return switch F to its normal position, he proceeds to return lever V1 to its normal position. When lever V1 reaches point E, relay G again becomes energized in its reverse direction, completing the re-

verse circuit for relay KK through contacts 74 and 72 of relays G and K respectively. The control circuit for lock L1, through contact 69, is again completed at point Y, and the movement of lever V1 can then be continued as far as its 5 B position. As lever V1 passes point C, the normal winding circuit for relay KK again becomes closed through contact 6 of lever V1, as previously traced, causing relay KK to open its contact 66 and close its contact 26. With lever V1 10 at the B position, relay G is again energized in its normal direction, causing the return of switch F to its normal position, whereupon the reverse circuit of relay KK becomes closed through contacts 55 and 57 of relays K and G respectively as 15 previously traced. The circuit for lock L1 is now completed, and hence the operation of lever V1 can be continued to its N position.

The operation of the apparatus for traffic moves other than I have traced will be readily understood from the foregoing description and the accompanying drawing.

Although I have herein shown and described only one form of remote control apparatus embodying my invention, it is understood that various changes and modifications may be made therein within the scope of the appended claims without departing from the spirit and scope of my invention.

Having thus described my invention, what I claim is:

1. In combination, a railway track switch, a polarized control relay which controls the operation of said switch to its normal or its reverse position according as said control relay is energized in its normal or its reverse direction respectively, a manually operable lever having a normal and a reverse position, an electric lock which when de-energized arrests the movement of said lever at a first and a second locking point 40 during the operation of said lever from its normal to its reverse position and at a third and a fourth locking point during the operation of said lever from its reverse to its normal position, a polarized indication relay the polar contacts of which while 45 said indication relay is de-energized remain closed in their normal or their reverse direction according as said indication relay has been next previously energized in its normal or its reverse direction respectively, means for energizing said control relay in its normal direction when said lever is at its first or its fourth locking point while a normal contact of said indication relay is closed, means for energizing said control relay in its reverse direction when said lever is at its second or 50 third locking point while a normal contact of said indication relay is closed, means for energizing said indication relay in its normal direction while said lever is in its normal or its reverse position or at a given point between said 55 second and fourth locking points, means for energizing said indication relay in its reverse direction while said control relay is energized when said switch occupies the position controlled by said energization of the control relay, and means 60 for energizing said lock when a reverse contact of said indication relay is closed.

2. In combination, a railway track switch, a polarized control relay which controls the operation of said switch to its normal or its reverse position according as said control relay is energized in its normal or its reverse direction respectively, a manually operable lever having a normal and a reverse position, an electric lock which when de-energized arrests the movement of said lever 70

- at a first and a second locking point during the operation of said lever from its normal to its reverse position and at a third and a fourth locking point during the operation of said lever from 5 its reverse to its normal position, a first polarized indication relay energized in its normal or its reverse direction according as said switch occupies its normal or its reverse position respectively, a second polarized indication relay the polar contacts of which while said second indication relay is de-energized remain closed in their normal or their reverse direction according as said second indication relay has been next previously energized in its normal or its reverse direction respectively, means for energizing said control relay in its 10 normal direction when said lever is at its first or fourth locking points while a normal contact of said second indication relay is closed, means for energizing said control relay in its 15 reverse direction when said lever is at its second or third locking points while a normal contact of said second indication relay is closed, means for energizing said second indication relay in its normal direction while said lever is in its normal or 20 its reverse position or at a given point between said second and fourth locking points, means for energizing said second indication relay in its reverse direction while said control relay and said first indication relay are both energized in their 25 normal direction or while said control relay and said first indication relay are both energized in their reverse direction, and means for energizing said lock when a reverse contact of said second indication relay is closed.
3. In combination, a railway signal, a control relay for said signal, a manually operable means, means including said manually operable means for controlling said relay, a neutral indication relay controlled by said signal, a polarized indication relay, means including said manually operable 30 means for energizing said polarized indication relay in a normal direction, means for energizing said polarized indication relay in the reverse direction when said signal indicates "stop" and said neutral indication relay is energized, and 35 indication means controlled by said polarized indication relay.
4. In combination, a railway signal, a control relay for said signal, a manually operable means, means including said manually operable means for controlling said relay, a neutral indication relay controlled by said signal, a polarized indication relay, means including said manually operable means for energizing said polarized indication relay in a normal direction, means for energizing 40 said polarized indication relay in the reverse direction when said signal indicates "stop" and said neutral indication relay is energized, an electric lock which when de-energized prevents the return of said manually operable means to its 45 normal position from a position for energizing said control relay, and means including a reverse contact of said polarized indication relay for energizing said electric lock.
5. In combination, a railway signal, a control 50 relay for said signal, a manually operable lever having a normal and a reverse position, means for energizing said relay when said lever is in its reverse position, a neutral indication relay controlled by said signal, a polarized indication relay, means including said lever for energizing said polarized indication relay in a normal direction, means for energizing said polarized indication relay in the reverse direction when said signal indicates "stop" and said neutral indication relay 55 is energized, a stick locking relay, a lock releas- 55
- ing relay, means for energizing said stick locking relay when said signal indicates "proceed", means for continuing the energization of said stick locking relay while said lock releasing relay is de-energized, a first means for energizing said lock releasing relay when said lever is in its reverse position and said signal has not completed its response to said control relay, a second means for energizing said lock releasing relay when a time-releasing device is operated to a reverse position 60 while said stick locking relay is energized, an electric lock which when de-energized prevents the return of said lever from its reverse to its normal position, and means for energizing said electric lock when a reverse contact of said polarized indication relay is closed and said time-releasing device is in its normal position and a back contact of said lock releasing relay is closed.
6. In combination, a railway switch, a signal governing the movement of traffic over said switch, two control wires and a common wire extending from a remote point to a point adjacent said switch, a first manually operable means at said remote point controlling said switch over the first of said control wires and said common wire, a second manually operable means at said remote point controlling said signal over the second of said control wires and said common wire, a first indication relay at said remote point controlled over said second control wire and said common wire in accordance with the position of said switch, and a second indication relay at said remote point controlled over said first control wire and said common wire in accordance with the position of said signal.
7. In combination, a railway track switch, a signal governing the movement of traffic over said switch, two control wires and a common wire extending from a remote point to a point adjacent said switch, a switch control relay for controlling said switch, a first and a second manually operable means at said remote point each having a normal and a reverse position, means including said first manually operable means in its reverse position for energizing said switch control relay over the first of said control wires and said common wire while said second manually operable means is in its normal position, a signal control relay for controlling said signal, means including said second manually operable means in its reverse position for energizing said signal control relay over said common wire and the second of said control wires when said switch control relay is de-energized, a switch indication relay, means controlled in accordance with the position of said switch for energizing said switch indication relay over said second control wire and said common wire, a signal indication relay, means controlled in accordance with the position of said signal for energizing said signal indication relay over said first control wire and said common wire, a first indication means controlled by said switch indication relay, and a second indication means controlled by said signal indication relay.
8. In combination, a railway signal, a manually operable means, a signal control relay controlling said signal, means including said manually operable means for controlling said signal control relay, a slow release relay, means for energizing said slow release relay while the arm of said signal is approaching its "stop" position, a second means for energizing said slow release relay when said signal relay is energized while said signal is indicating "stop", an indication 70
- 75

relay, means for energizing said indication relay when said signal indicates "stop" while a front contact of said slow release relay is closed, and indication means controlled by said indication 5 relay.

9. In combination, a railway switch, signals governing traffic over said switch, a switch control relay, a signal control relay, a switch lever, a signal lever, a switch indication relay, a signal 10 indication relay, a combined switch control and signal indication wire 41, a combined signal control and switch indication wire 60, a common wire 30, a circuit for said switch control relay controlled by said switch lever and including a 15 normal signal lever contact and a back contact of said signal control relay as well as said wires 41 and 30, a circuit for said signal control relay controlled by said signal lever and including a back contact of said switch control relay and 20 said wires 60 and 30, a circuit for said switch indication relay controlled by said switch and including said wires 60 and 30, a circuit for 25 said signal indication relay controlled by said signals and including contacts on said signal lever as well as said wires 41 and 30, and indication devices controlled by said indication relays.

10. In combination, a railway switch, a signal governing the movement of traffic over said switch, two control wires and a common wire, 30 a circuit including said common wire and the first of said control wires for controlling said switch, a circuit including said common wire and the second of said control wires for controlling said signal, a first indication device, a second 35 indication device, a circuit controlled by said switch and including said common wire and said second control wire for controlling said first indication device, and a circuit controlled by said signal and including said common wire and said 40 first control wire for controlling said second indication device.

11. In combination, a railway switch, a signal to govern the movement of traffic over the switch, operating means for the switch and signal, and a relay controlled by traffic conditions 45 for governing the operation of the switch and of the signal by said operating means, said relay being arranged to permit movement of the switch only when energized and to permit the clearing 50 of the signal only when deenergized.

12. In combination, a railway switch, a signal to govern the movement of traffic over the switch, operating means for the switch and signal, a relay for governing the operation of the switch 55 and of the signal by said operating means and arranged to permit a movement of the switch only when energized and to permit the clearing of the signal only when deenergized, means responsive to traffic conditions to effect energization of said relay, and a remote controlled means to at times effect deenergization of said relay.

13. In combination, a railway switch, a signal to govern the movement of traffic over the switch, operating means for the switch and signal, a 60 relay for governing the operation of the switch and of the signal by said operating means and arranged to permit a movement of the switch only when energized and to permit the clearing of the signal only when deenergized, a traffic 65 controlled means, a remote controlled device, and a circuit means jointly controlled by said traffic controlled means and said remote controlled device to govern the energizing and deenergizing of said relay.

14. In combination, a track switch of a rail-

way system, a switch machine for operating said switch to normal or reverse, a signal associated with said switch for governing movement of traffic over said switch, and a relay which if picked up closes a circuit for clearing said signal and when released closes a circuit for controlling said switch machine to operate the switch to normal or reverse, whereby said switch machine cannot be operated unless said signal is at stop. 5

15. In combination, a track switch of a railway system, a switch machine for operating said switch, a plurality of signals associated with said switch for governing movement of traffic over said switch, and a relay having a contact which 10 if in its energized position closes a circuit for clearing any one of said signals and when deenergized closes a circuit for controlling said switch machine, whereby said switch machine cannot be operated unless all of said signals are 15 at stop.

16. In combination, a track switch, a switch machine for operating said track switch, a signal for governing movement of traffic over said track switch, a signal control relay which if energized 20 permits clearing of said signal, a switch control relay for controlling said switch machine, two levers, two line circuits, one lever for controlling the energization of said signal control relay over one line circuit and the other lever for controlling 25 the energization of said switch control relay over the other line circuit, and a contact in the control circuit of said switch control relay closed only if said signal control relay is deenergized. 30

17. In combination, a track switch, a switch machine for operating said track switch, a signal for governing movement of traffic over said track switch, a signal control relay which if energized 35 permits clearing of said signal, a switch control relay for controlling said switch machine, two levers, one for energizing said signal control 40 relay and the other for energizing said switch control relay, and a contact in the control circuit of said switch control relay closed only if said signal control relay is deenergized and has 45 been deenergized for a predetermined period of time.

18. In combination, a section of railway track including a track switch, signals for governing traffic through said section; means for controlling the switch and signals from a remote point comprising switch and signal control levers at said remote point, and switch and signal control relays adjacent said section; a switch control circuit including contacts of the switch control 55 lever, a first line circuit and the switch control relay; a signal control circuit including contacts of the signal control lever, a second line circuit and the signal control relay; a stick track relay for the section connected to the rails through 60 its own front contact, a shunt for said track relay contact comprising a back contact of the signal control relay, and means for controlling said switch by said track relay comprising a front contact of the track relay included in said switch 65 control circuit.

19. In combination, a track switch of a railway system, a switch machine for operating said switch to normal or reverse, a signal associated with said switch for governing movement of traffic over said switch, a signal control relay for clearing the signal when said relay is energized, and a contact independent of said signal and closed when the control circuit of said relay is open and the relay thereby deenergized and in- 70 75

cluded in a circuit for controlling said switch machine to operate the switch to normal or reverse, whereby said switch machine cannot be operated unless the signal control relay is deenergized so that the signal is at stop.

20. In combination, a track switch of a railway system, a switch machine for operating said switch, a plurality of signals associated with said switch for governing movement of traffic over said switch, a signal control relay for clearing any one of said signals when said relay is energized, and a contact independent of said signals and closed when the control circuit of said relay is open and the relay thereby deenergized and included in a circuit for controlling said switch machine, whereby said switch machine cannot be operated unless the signal control relay is deenergized so that all of said signals are at stop.

21. In combination, a track switch of a railway system, a switch machine for operating said switch, a signal associated with said switch for governing movement of traffic over said switch, contacts which in a first position close a circuit for clearing said signal and which in a second position close a circuit for controlling said switch machine, and timing means responsive to the movement of said contacts from said first position for delaying the movement of said contacts to said second position, whereby said switch machine cannot be operated until said signal has been at stop for a predetermined time interval.

22. In combination, a track switch of a railway system, a switch machine for operating said switch, a plurality of signals associated with said switch for governing movement of traffic over said switch, contacts which in a first position close a circuit for clearing any one of said signals and which in a second position close a circuit for controlling said switch machine, and timing means responsive to the movement of said contacts from said first position for delaying the movement of said contacts to said second position, whereby said switch machine cannot be operated until said signals have been at stop for a predetermined period of time.

23. In combination, a track switch, a switch machine for operating said track switch, a signal for governing movement of traffic over said track switch, a signal control relay which if energized permits clearing of said signal, a switch control relay for controlling said switch machine, two levers, one for energizing said signal control relay and the other for energizing said switch control relay, and a contact in the control circuit of said switch control relay closed only at the end of a predetermined time interval after the lever associated with the signal control relay has been moved to a position to deenergize said relay.

24. In a remote control system, a two position railway track switch, a signal for governing traffic over the switch, a switch lever having two positions corresponding to the two positions of the track switch, a signal lever having a proceed and a stop position, means responsive to a movement of the switch lever from one position to the other to operate the switch to a corresponding position, means responsive to a movement of the signal lever to clear the signal or to put it to stop, means including contacts controlled by the signal lever for preventing operation of the switch control relay by the switch lever when the signal lever is in the proceed position, and means effective when the signal lever is moved to put the signal to stop for delaying the closing of said contacts whereby said switch cannot be operated

until the signal has been at stop for a predetermined period of time.

25. In combination, a section of railway track including a track switch, signals for governing traffic through said section; means for controlling the switch and signals from a remote point comprising switch and signal control levers at said remote point, and switch and signal control relays adjacent said section; a switch control circuit including contacts of the switch control lever, a first line circuit and the switch control relay; a signal control circuit including contacts of the signal control lever, a second line circuit and the signal control relay; and means for opening the switch control circuit when the signal control circuit is closed to clear a signal regardless of the positions assumed by the signals.

26. In combination, a section of railway track including a track switch, signals for governing traffic through said section; means for controlling the switch and signals from a remote point comprising switch and signal control levers at said remote point, and switch and signal control relays adjacent said section; a switch control circuit including contacts of the switch control lever, a first line circuit and the switch control relay; a signal control circuit including contacts of the signal control lever, a second line circuit and the signal control relay; means for opening the switch control circuit when the signal control circuit is closed to clear a signal, and means for preventing the closing of the switch control circuit when the signal control circuit is opened to put the signal to stop, until the signal has been at stop for a predetermined period of time.

27. In combination, a section of railway track including a track switch, signals for governing traffic through said section; means for controlling the switch and signals from a remote point comprising switch and signal control levers at said remote point, and switch and signal control relays adjacent said section; a switch control circuit including contacts of the switch control lever, a first line circuit and the switch control relay; a signal control circuit including contacts of the signal control lever, a second line circuit and the signal control relay; means for opening the switch control circuit when said section is occupied, and means for opening said switch control circuit when the signal control circuit is closed to clear a signal regardless of the positions occupied by the signals.

28. In combination, a section of railway track including a track switch, signals for governing traffic through said section; means for controlling the switch and signals from a remote point comprising switch and signal control levers at said remote point, and switch and signal control relays adjacent said section; a switch control circuit including contacts of the switch control lever, a first line circuit and the switch control relay; a signal control circuit including contacts of the signal control lever, a second line circuit and the signal control relay; means for opening the switch control circuit when the signal control circuit is closed to clear a signal, and means for maintaining said circuit open when a train accepts the signal and moves through the section, until said section becomes unoccupied and the signal control circuit has been opened.

29. In combination, a section of railway track including a track switch, signals for governing traffic through said section; means for controlling the switch and signals from a remote point comprising switch and signal control levers at

said remote point, and switch and signal control relays adjacent said section; a switch control circuit including contacts of the switch control lever, a first line circuit and the switch control relay; a signal control circuit including contacts of the signal control lever, a second line circuit and the signal control relay; means for opening the switch control circuit when the signal control lever is moved to a position to clear a signal, and means for maintaining said circuit open when a train accepts the signal and moves through the section, until said section becomes unoccupied and the signal control lever has been moved to a position to open the signal control circuit.

30. In combination, a section of railway track including a track switch, signals for governing traffic through said section; means for controlling the switch and signals from a remote point comprising switch and signal control levers at said remote point, and switch and signal control relays adjacent said section; a switch control circuit including contacts of the switch control lever, a first line circuit and the switch control relay; a signal control circuit including contacts of the signal control lever, a second line circuit and the signal control relay; means for opening the switch control circuit when the signal control lever is moved to a position to clear a signal, and means for preventing the closing of the switch control circuit for a predetermined period of time when the signal lever is moved from such position to put the signal to stop.

31. In combination, a railway track switch, a signal governing the movement of traffic over said switch, two control wires and a common wire extending from a remote point to a point adjacent said switch, a switch control relay for controlling said switch, a signal control relay for controlling said signal, a switch lever having a normal and a reverse position and a signal lever having a clear and a stop position and both located at said remote point; means including said signal lever, one of the control wires, and the common wire for controlling the signal control relay to clear the signal or to put it to stop in accordance with the position of the signal lever; and means including the switch lever, the other control wire, the common wire, and a back contact of the signal control relay for energizing the switch control relay to operate the switch to a normal or a reverse position in accordance with the position of the switch lever; whereby the switch may be operated only when the signal control relay is deenergized.

32. In combination, a railway track switch, a signal governing the movement of traffic over said switch, two control wires and a common wire extending from a remote point to a point adjacent said switch, a switch control relay for controlling said switch, a signal control relay for controlling said signal, a switch lever having a normal and a reverse position and a signal lever having a clear and a stop position and both located at said remote point; means including said signal lever, one of the control wires, and the common wire for controlling the signal control relay to clear the signal or to put it to stop in accordance with the position of the signal lever; and means including the switch lever, the other control wire, the common wire, and a contact of the signal lever closed only when said lever is in a position to put the signal to stop, for energizing the switch control relay to operate the switch to a normal or to a reverse position in accordance with the position of the switch lever.

33. In combination, a railway track switch, a signal governing the movement of traffic over said switch, two control wires and a common wire extending from a remote point to a point adjacent said switch, a switch control relay for controlling said switch, a signal control relay for controlling said signal, a switch lever having a normal and a reverse position and a signal lever having a clear and a stop position and both located at said remote point; means including said signal lever, one of the control wires, and a common wire for controlling the signal control relay to clear the signal or to put it to stop in accordance with the position of the signal lever; and means including the switch lever, the other control wire, the common wire, and a contact of the signal lever closed only when said lever is in a position to put the signal to stop and has been in such position for a predetermined period of time, for energizing the switch control relay to operate the switch to a normal or to a reverse position in accordance with the position of the switch lever; whereby the switch cannot be operated unless the signal lever has been returned to the stop position and the signal has been at stop for a predetermined period of time.

34. In combination, a railway track switch, a signal governing the movement of traffic over said switch, two control wires and a common wire extending from a remote point to a point adjacent said switch, a switch control relay for controlling said switch, a signal control relay for controlling said signal, a switch lever having a normal and a reverse position and a signal lever having a clear and a stop position and both located at said remote point; means including said signal lever, one of the control wires, and a common wire for controlling the signal control relay to clear the signal or to put it to stop in accordance with the position of the signal lever; and means including the switch lever, the other control wire, the common wire, and a time controlled contact closed only when the signal control relay has been deenergized for a predetermined period of time, for energizing the switch control relay to operate the switch to a normal or to a reverse position in accordance with the position of the switch lever; whereby the switch cannot be operated unless the signal has been at stop for a predetermined period of time.

35. In combination, a railway track switch, a signal governing the movement of traffic over said switch, two control wires and a common wire extending from a remote point to a point adjacent said switch, a switch control relay for controlling said switch, a signal control relay for controlling said signal, a switch lever having a normal and a reverse position and a signal lever having a clear and a stop position and both located at said remote point; means including said signal lever, one of the control wires, the common wire, and a back contact of the switch control relay for controlling the signal control relay to clear the signal or to put it to stop; and means including said switch lever, the other control wire, the common wire, and a back contact of the signal control relay, for energizing the switch control relay to operate the switch to a normal or reverse position in accordance with the position of the switch lever.

36. In a remote control system, a two position railway track switch at a remote point; a plu- 75

- rality of signals for governing traffic over said switch, including one for each direction for each position of the switch; a switch lever having two positions corresponding to the two positions of the switch, a signal lever having two proceed positions and a stop position, a polarized switch control relay responsive to a movement of the switch lever from one position to the other to operate the switch to a corresponding position, a polarized signal control relay for clearing a signal for one direction or the other responsive to a movement of the signal lever to one proceed position or the other, or for putting all signals at stop when said lever is in its stop position; means including contacts controlled by the signal lever for preventing operation of the switch control relay by the switch lever when the signal lever is in a proceed position, and means effective when the signal lever is moved away from such position to delay the closing of said contacts, whereby said switch cannot be operated until all signals have been at stop for a predetermined period of time.
37. In combination, a two position railway track switch; a plurality of signals for governing traffic over said switch, including one for each direction for each position of the switch; two control wires and a common wire extending from a remote point to a point adjacent said switch, a polarized switch control relay for controlling said switch, a polarized signal control relay for controlling said signals; a switch lever having a normal and a reverse position, and a signal lever having two proceed positions and a stop position both located at said remote point; means including said signal lever, one of the control wires and the common wire for controlling the signal control relay to clear a signal for one direction or the other in accordance with the position of the switch when the signal lever is moved to one proceed position or the other, or to put all signals to stop when moved from such positions; and means including the switch lever, the other control wire, the common wire, and a back contact of the signal control relay for energizing the switch control relay to operate the switch to one position or the other in accordance with the position of the switch lever; whereby the switch may be operated only when the signal control relay is deenergized.
38. In combination, a two position railway track switch; a plurality of signals for governing traffic over said switch, including one for each direction for each position of the switch; two control wires and a common wire extending from a remote point to a point adjacent said switch, a polarized switch control relay for controlling said switch, a polarized signal control relay for controlling said signals; a switch lever having a normal and a reverse position, and a signal lever having two proceed positions and a stop position both located at said remote point; means including said signal lever, one of the control wires and the common wire for controlling the signal control relay to clear a signal for one direction or the other in accordance with the position of the switch when the signal lever is moved to one proceed position or the other, or to put all signals to stop when moved from such positions; and means including the switch lever, the other control wire, the common wire, a time controlled contact closed at the end of a predetermined time interval following a movement of the signal lever from a proceed position for energizing the switch control relay to operate the switch to a normal or to a reverse position in accordance with the position of the switch lever when all signals have been at stop for said time interval.
39. In combination, a plurality of energy-responsive devices, a manually operable device, means controlled by said manually operable device for controlling said energy-responsive devices, an indication means, and means controlled by said manually operable device for energizing said indication means when the condition of said energy-responsive devices does not correspond to the condition of said manually operable device. 5
40. In combination, a plurality of railway traffic governing devices, a control means for controlling said traffic governing devices, an indication means, and means controlled by said control means for energizing said indication means when the condition of any of said railway traffic governing devices does not correspond to the condition of said control means. 10
41. In an interlocking system for railways, a railway track switch, a signal for governing the movement of traffic over the switch, a control circuit for controlling the switch, a manually operable lever for controlling the signal, means for closing the control circuit including a short time element device rendered effective when said lever is moved to put the signal to stop, a long time 15 element device, and means for at times governing the control circuit by the long time element device. 20
42. In combination with a railway switch, a signal governing traffic over said switch, a lever controlling said signal, locking means at times preventing operation of said switch, a first time element device controlled by said lever and controlling said locking means, a second time element device, and apparatus controlled in accordance 25 with traffic conditions adjacent said switch for at times placing said locking means under the control of said second time element device. 30
43. In combination with a detector track section containing a railway switch and provided with a track relay, a signal governing traffic into said section, a lever controlling said signal, locking means at times preventing operation of said switch, a first time element device controlled by said lever and controlling said locking means, a second time element device, and apparatus controlled by said track relay for at times placing said locking means under the control of said second time element device. 35
44. In combination with a railway track switch and a signal for governing the movement of traffic over the switch, a locking circuit adapted when closed to permit operation of the switch, a control lever effective in a first position to close a contact for clearing the signal and in a second 40 position to close a contact controlling said locking circuit, a time element device controlled by the lever for delaying the closing of the locking circuit for a predetermined time interval after the lever is moved from said first position, a second time element device for delaying the closing of the locking circuit for a longer time interval after the lever is moved from said first position, and means controlled by traffic conditions for at times requiring operation of said second time element device to permit the closing of said locking circuit. 45
45. In combination with a section of railway track containing a track switch, a signal for governing the movement of traffic over the switch, a 50

locking circuit, means effective when said circuit is open for at times preventing operation of the switch, a control lever effective in a first position to close a contact for clearing the signal and in 5 a second position to close a contact controlling the locking circuit, a first time element device for delaying the closing of said locking circuit for a predetermined time interval after said lever is moved to its second position, a second time element device, and means effective if said lever is moved to its second position when said section is unoccupied for placing said locking circuit under the control of said second time element device.

46. In combination, a railway track switch, a 15 signal governing traffic over said switch, manual means for controlling said signal, locking means for at times preventing power operation of said switch, a first time element device controlled by said manual means and controlling said locking 20 means, a second time element device at times controlling said locking means, a stick relay controlled by traffic conditions adjacent said switch, and means including a contact of said stick relay for at times requiring operation of said second 25 timing device to permit the release of said locking means.

47. In combination, a detector track section containing a railway switch, a signal for governing the movement of traffic over said switch, 30 manual control means for said signal, and means effective after the manual control means is operated to put the signal to stop to temporarily withhold control of the switch, said control being withheld for a time interval which is relatively 35 long or short depending on whether or not an approaching train has passed the signal at the time said manual control means is operated.

48. In combination, a section of railway track, a track switch in said section, a signal governing traffic over said track switch, locking means which if deenergized is at times effective to prevent power operation of said switch, a control lever having a contact closed in a first position for clearing said signal and a contact closed in a 45 second position included in an energizing circuit for said locking means, means for preventing the closing of said energizing circuit for a predetermined period of time following the movement of the control lever from its first to its second position provided an approaching train has passed 50 the signal, and means for increasing said period of time in the event said movement of the control lever occurs before such train has passed the signal.

55. 49. In a remote control system, a railway track switch, a polarized control relay for operating the switch, a control lever for operating said relay, locking means for at times preventing the operation of said relay by said lever, and means effective when said locking means is released requiring the energization of said relay in a direction corresponding to the last operated position of the switch before said relay can be energized in the opposite direction to operate the switch.

65. 50. In a remote control system, a railway track switch, a polarized control relay for operating the switch, a control lever for operating said relay, locking means for at times preventing the operation of said relay by said lever, and means preventing the energization of said relay in a direction to operate the switch when said locking means is released unless said relay is first energized in a direction corresponding to the last operated position of the switch.

75. 51. In a remote control system, a railway track

switch, a polarized control relay for operating the switch, a control lever for operating said relay, locking means for at times preventing the operation of said relay by said lever, and means effective when said locking means becomes deenergized 5 requiring the lever and the switch to be in corresponding positions before said relay can be operated to operate the switch.

52. In combination, a railway track switch, a polarized control relay for operating the switch, 10 a locking relay, a control lever; a circuit for said control relay including a front contact of said locking relay and pole changing contacts controlled by said control lever for energizing said control relay in one direction or the other in accordance with the position of said lever when said locking relay is energized; locking means for preventing the energization of said circuit to reverse the control relay when said locking relay becomes energized, and means responsive to the 15 energization of said circuit in a direction to retain said control relay in its last operated position for releasing said locking means.

53. In combination, a railway track switch, a polarized control relay for operating the switch, 25 a control lever, a control circuit including said relay and contacts controlled by said lever for energizing said relay in a normal or reverse direction to operate the switch to its normal or reverse position, locking means for at times preventing the operation of said control relay for operating the switch, and means for releasing said locking means effective only when the lever and the switch occupy corresponding positions.

54. In a remote control system, a railway track 35 switch, a control lever, a polarized control relay actuated by said lever for operating said switch, locking means for at times preventing the actuation of said control relay by said control lever, and means for releasing said locking rendered 40 effective by a movement of said lever to a position corresponding to the last operated position of said switch.

55. In a remote control system, a railway track switch, a control lever, a polarized control relay 45 actuated by said lever for operating said switch, locking means for at times preventing the actuation of said control relay by said control lever, and other means effective to prevent the actuation of said control relay by said control lever to 50 operate the switch unless said lever is first moved to a position to energize said control relay to a position corresponding to the last operated position of the switch.

56. In a remote control system, a railway track 55 switch, a polarized control relay for operating the switch, a control lever, a circuit including said control relay and contacts controlled by said lever and adapted at times to be energized to actuate said relay to operate the switch to a position corresponding to the position to which said lever is moved, and means requiring the placing of the lever in a position corresponding to that of the switch to render said circuit effective.

57. In combination with a railway track switch, 65 a polarized control relay for the switch, a control circuit for said relay, locking means controlled in accordance with traffic conditions adjacent the switch for at times opening said circuit, a pole-changer at a point remote from the switch for 70 energizing said circuit, manually operable means for reversing said pole-changer, and means for preventing the reversal of said pole-changer if said manually operable means is actuated when said control circuit is open.

58. In combination with a railway track switch, a polarized control relay for the switch, a control circuit for said relay closed only when traffic conditions are favorable for operating the switch,
5 a pole-changer at a remote point for controlling the polarity of the current supplied to said circuit, and means for preventing the reversal of the polarity of the current supplied to said circuit unless said pole-changer is operated when said
10 circuit is closed.

59. In a centralized traffic controlling system for railroads, a track switch, a control lever, a switch control relay for operating said track switch when actuated by said control lever, signals
15 for setting up routes over said track switch, locking means preventing actuation of said switch control relay whenever a route is set up over said track switch and for at least a predetermined time after the signal for that route is put to stop
20 irrespective of the presence of a train approaching said switch, and means requiring said control lever to be in correspondence with said track switch subsequent to the unlocking of said locking means before said operating means can be
25 actuated by said control lever.

60. In combination, a track switch, a switch machine for operating said track switch, a control lever, signals governing traffic over said track switch, approach locking means conditioned to prevent operation of said switch machine when said signals are conditioned to allow traffic over said track switch, a control circuit for said switch machine governed by said control lever subject to said approach locking means, means releas-

ing said approach locking means and ineffective for at least a predetermined time after said signals have been conditioned to prevent movement of traffic over said track switch, said releasing means acting irrespective of a train approaching
5 the switch, and means preventing the control of said switch machine by said control lever subsequent to the releasing of said approach locking means if said control lever is out of correspondence with said track switch.
10

61. In combination; a track switch; a switch machine for operating said track switch; signals for governing traffic over said track switch; a switch machine control lever; a switch machine control relay for controlling the operation of said
15 switch machine; a circuit for said switch machine control relay governed by said control lever; approach locking means conditioned to prevent the governing of said switch machine control relay by said control lever when said signals are conditioned to allow the passage of traffic over said track switch; means restoring said approach locking means effective following at least a predetermined time after said signals have been conditioned to prevent movement of
20 traffic over said track switch and said restoring means acting irrespective of a train approaching said switch; and means preventing the control of said switch machine control relay by said control lever subsequent to the restoring of said approach
25 locking means if said control lever is out of correspondence with said track switch upon such restoration.

HARRY C. VANTASSEL.
